UNITED STATES PATENT OFFICE.

ARTHUR J. MOXHAM, OF JOHNSTOWN, PENNSYLVANIA.

ROLLS FOR ROLLING GIRDER-RAILS.

SPECIFICATION forming part of Letters Patent No. 378,210, dated February 21, 1889.

Application filed December 19, 1887. Serial No. 258,286. (No model.)

To all whom it may concern:

Be it known that I, ARTHUR J. MOXHAM, of Johnstown, in the county of Cambria and State of Pennsylvania, have invented new and 5 useful Rolls for the Rolling of Two Finished Forms of Girder-Rails, which invention is fully set forth and illustrated in the following specification and accompanying drawings.

The object of this invention is to roll two 10 forms of girder-rail, each form finished for use, the one finished form to be converted into the other when required.

The invention will first be described in detail, and then particularly set forth in the 15 claims.

In the accompanying drawings, Figure 1 illustrates in front elevation a set of roughing-rolls containing one flattening-pass, one edging-pass, and one dummy pass, in the order 20 named, commencing at the left of the figure. Fig. 2 illustrates, also in front elevation, another set of roughing-rolls, whose first two passes from the left are edging-passes and whose remaining pass is a dummy pass. Fig. 25 3 illustrates, also in front elevation, a set of finishing-rolls all of whose passes, save the final pass on the right of the figure, are edging-passes, said final pass being a flange or tram-curving pass, which may or may not be 30 used, as occasion requires. Fig. 4 illustrates in end elevation a rail of the form as finished in the last pass but one of Fig. 3. Fig. 5 illustrates the same rail when the side flange of its head has been upturned after being put 35 through the last pass in Fig. 3.

In said figures the upper rolls are respectively indicated by the letter A and the lower rolls by the letter B, and the passes between the rolls are indicated by numbers from 1 to 40 12, inclusive. Pass No. 1 is a flattening-pass, pass No. 2 an edging pass, and pass No. 3 a dummy pass. Passes 4 and 5 are edging-passes, and pass No. 6 is a dummy pass. Passes 7, 8, 9, 10, and 11 are edging-passes, 45 and pass 12 a flange or tram-curving pass, which latter pass may or may not be used, as hereinbefore stated, its purpose being to bend up the flange *f* of the rail previously rolled in pass No. 11. It will be observed that in the 50 above-named dummy passes the bottoms or

lower parts of said passes, instead of being made flat, are beveled or offset on one side, as shown at the points *p*. By thus shaping said dummy passes the use of the dummy passes can be extended beyond the point at which 55 the offset for the head portion is rolled in, and it so aids in the rolling by hastening the operation of reducing the metal to the desired finished form.

It will be observed that there are these differences between the invention described in my application Serial No. 258,285, herewith filed, and the invention herein described: In said application a blank is rolled from which two forms of rail can be subsequently rolled 60 from said same blank by special mechanism; but by the invention herein described the finished rail is rolled ready for use in the form as it leaves pass No. 11, and can then be either used in such form or put through pass No. 12, 65 which turns up its flange *f*, changing its shape from that shown in Fig. 4 to that shown in Fig. 5, as already explained, and the rolls are essentially different in the shape and form of the dummy pass.

I do not limit myself to the exact number or distribution of passes shown, as the number of passes and their distribution into roughing and finishing passes is to a certain extent arbitrary, being influenced by the length and 70 diameter of the rolls, a light train of rolls calling for more passes with lighter draft than a heavy roll-train. It is also evident that the rolls can, if desired, be made three-high, instead of two-high, as shown.

Having thus fully described my said improvement as of my invention, I claim—

1. Rolls for rolling girder-rails, provided with one or more dummy passes having a bottom offset, as at *p*, substantially as and for the 80 purposes set forth.

2. Rolls for rolling girder-rails, provided with passes substantially of the shape or form shown in the accompanying drawings, and numbered from 1 to 12, inclusive, as and for 95 the purposes set forth.

ARTHUR J. MOXHAM.

Witnesses:

C. R. POWELL,
C. M. JOHNSON.
